UNITED STATES PATENT OFFICE.

JACOB A. STONER, OF ALTOONA, PENNSYLVANIA.

RAILWAY-TIE.

981,954.

Specification of Letters Patent. Patented Jan. 17, 1911.

Application filed August 3, 1909. Serial No. 511,012.

To all whom it may concern:

Be it known that I, JACOB A. STONER, a citizen of the United States, residing at Altoona, in the county of Blair and State of Pennsylvania, have invented certain new and useful Improvements in Railway-Ties, of which the following is a specification.

The present invention relates more particularly to ties of the composite type, and 10 the object in view is to provide a structure, which is very strong, and can be cheaply produced, said structure including rail-supporting cushion blocks of wood that are effectively fastened in place, and yet may be 15 removed when worn out.

A further object is to provide a structure of the above character having an extended supporting base, around which the ballast may be readily tamped.

20 The preferred embodiment of the invention is illustrated in the accompanying drawings, wherein:

Figure 1 is a top plan view of the tie, with the cushion blocks removed. Fig. 2 is a 25 side elevation of the same, partially in section, with the cushion blocks and rails in place. Fig. 3 is a bottom plan view of the structure. Figs. 4 and 5 are cross sectional views therethrough. Fig. 6 is an end elevation of the same.

Similar reference numerals designate corresponding parts in all the figures of the drawings.

In the embodiment disclosed, a hollow 35 body 7 is employed that may be cast in one piece, as shown, or made up of a series of sheet metal sections riveted together. The body is provided with a series of chambers 8 having communication with the outer air 40 through openings or ports 9. Said body is furthermore formed with a pair of rail cushion receiving sockets 10 having open upper ends and bottoms 11, the latter being provided with cushion ejecting and drain 45 openings 12. The side walls of the sockets have beveled inwardly extending tapered 50 ribs 13 that constitute retaining spurs, and it will be observed that the lower edges of the side walls which are provided with the spurs 13 terminate short of the bottom of the

tie body and thus permit of a yielding effect when the cushions are crowded in place. The opposite lower edges of the end portions of the body are also provided with outstanding flanges 14, which, as shown in Figs. 4 55 and 5, are downwardly curved, so that extended bases are produced that are cupped or dished, as shown at 15.

It will be observed that the top of the body, at the sockets 10, is cut away, and in 60 said sockets are placed rail-supporting cushion blocks 16 of wood. These blocks are arranged with the grain on edge or vertical, as will be clear by reference to Fig. 2. The blocks have the ribs or retaining spurs 13 65 embedded therein, and to further fasten said blocks in place, lag screws 17 are passed through the side walls of the sockets into the blocks. The usual rails 18 are placed upon the blocks and are supported thereby, being 70 held in place by spikes 19 driven into the blocks.

It will be obvious that this structure is an exceedingly simple one, and yet very durable. The end portions have extended bases, and 75 the flanges, which produce the same, being downwardly curved, permit the ballast to be packed or tamped about said bases without difficulty. However, should the cushion blocks become badly worn or injured, they 80 may be removed by driving a suitable instrument through the openings 12, and said openings also constitute drains to permit the outlet of moisture, which would otherwise accumulate in the sockets.

From the foregoing, it is thought that the construction, operation and many advantages of the herein described invention will be apparent to those skilled in the art, without further description, and it will be 90 understood that various changes in the size, shape, proportion and minor details of construction, may be resorted to without departing from the spirit or sacrificing any 95 of the advantages of the invention.

Having thus fully described my invention, what I claim as new, and desire to secure by Letters Patent, is:—

A railway tie comprising a metallic tie body provided with cushion receiving sock- 100

ets having yielding side walls whose lower edges terminate short of the bottom of the tie body and are provided with inwardly projecting retaining spurs, rail supporting
5 cushion blocks fitting said sockets and engaged by said spurs and fastenings for said blocks.

In testimony whereof I hereunto affix my signature in the presence of two witnesses.

JACOB A. STONER.
